UNITED STATES PATENT OFFICE.

JOHN EDMAN, OF MINNEAPOLIS, MINNESOTA, ASSIGNOR TO PATRICK M. POWER, OF CHICAGO, ILLINOIS.

CONVERTIBLE STOCK AND FREIGHT CAR.

Application filed August 6, 1920. Serial No. 401,758.

To all whom it may concern:

Be it known that I, JOHN EDMAN, a citizen of the United States, residing at Minneapolis, in the county of Hennepin and 5 State of Minnesota, have invented certain new and useful Improvements in Convertible Stock and Freight Cars; and I do hereby declare the following to be a full, clear, and exact description of the invention, such 10 as will enable others skilled in the art to which it appertains to make and use the same.

My present invention relates to box cars and is directed to the improvement of the 15 side door structures. Generally stated, the invention consists of the novel devices and combinations of devices hereinafter described and defined in the claims.

Box cars for shipping various kinds of 20 goods or materials must be completely closed structures, while for the shipping of live stock, they should be more than well ventilated, that is, should have large openings or 25 air passages through the side door openings through which light, as well as air may pass in a very free manner.

My invention combines sliding gate bars 30 with the sliding side doors of box cars in a novel manner, hereinafter described, and whereby the side door openings may be entirely closed, entirely opened, or closed by more or less of the gate bars, at will, and whereby the desired results above indicated 35 may be accomplished.

The invention is illustrated in the accompanying drawings wherein like characters indicate like parts throughout the several views.

Referring to the drawings:

Fig. 1 is a side elevation showing the central portion of a box car and illustrating 40 my invention applied thereto;

Fig. 2 is a horizontal section taken on the line 2—2 of Fig. 1;

Fig. 3 is a vertical section taken on the line 3—3 of Fig. 1, some parts being broken away, and the parts being shown on a larger scale than in Fig. 1;

Fig. 4 is a fragmentary perspective, 50 some parts being sectioned illustrating the manner in which the gate bars are interlocked to the sliding side door and one of the door posts; and

Fig. 5 is a fragmentary perspective show-

ing a portion of the door and means for 55 locking the same to the car body.

The body of the box car is indicated by the numeral 6 and its side door openings by the numeral 7.

Each door opening 7 is adapted to be 60 opened and closed by a sliding side door 8 secured to horizontal upper and lower sliding bars 9 and 10 arranged to move, respectively, above and below the door opening 7. The upper bar 9 is arranged to slide through 65 guide brackets 11 fixed to the side of the car, while the lower bar 10 is shown as arranged to slide through a guide bracket 12 and guide lug 13 secured on the side of the car body. The upper bar 9 is about three times 70 as long as the door 8 is wide, and the said door is secured to the intermediate portion thereof. The lower bar 10 is a little more than twice as long as the door 8 is wide and the said door is secured to the right hand 75 portion thereof, directions being taken in respect to Figs. 1 and 2.

The door 8, at its left hand edge, as viewed in Fig. 1, is provided with a laterally inwardly projecting flange afforded by an 80 angle iron 14 riveted, bolted, or otherwise rigidly secured thereto in such manner that the flange of said angle will engage the door post 15 when the door is moved outward, or 85 to an extreme open position.

Mounted to slide through openings in the door post 16 that is opposite to the door post 15, and to move within the side of the car between the inner and outer sheathing, is a plurality of horizontally disposed vertically spaced gate bars 17. At their outer ends, these gate bars are provided with latch plates 18 formed on their under edges with lock notches 19, and, at their outer ends, 90 with undercut cam surfaces 20.

The door posts 15 are provided with pockets 21 with which the beveled, or undercut, ends of the latch plates 18 of gate bars 17, engage. The inwardly projecting flange of the angle bar 14 is provided with slots 22 100 through which the outer end of the latch plates 18 may be projected, so as to engage their notches 19 with the said flange, and thereby interlock the gate bars to said angle 14 for sliding movements with the door 8.

The pockets 21 in the post 15 are so located that when the ends of the latch plates 18 are, by opening movement of the door 8,

moved into the pockets 21, the latter will hold the same down and positively interlocked to the flange of the angle bar 14, so that it will be impossible to disconnect the 5 gate bars from the door, or from the post 15, when the door is in extreme open position.

The gate bars are adapted to be slid back into the wall of the car body, so as to leave the door passage completely open, or entirely free for passage therethrough. When the door is slid to the left, or slightly toward a closed position, the outer ends of the gate bars may be raised so that their latch plates may be freely moved endwise, 10 either into or out of interlocking engagement with the flange of the angle bar 14. It therefore follows that all or any desired 15 number of the gate bars may be interlocked to the door. Obviously, for keeping hogs in 20 a car, more of the gate bars will be required than for keeping cattle, for example, within the car. The above arrangement provides for such, and other adjustments. Obviously, 25 when the gate bars are locked to the door flange and the door is secured in its extreme open position, as above described, there is no possibility of animals within the car disconnecting the gate bars from the door and door post.

30 When the door 8 is slid, its guide bars 9 and 10 move with it through the guiding devices described. For locking the door, at will, either in a closed position, or in an extreme open position, I provide a lock device which comprises an upright rock shaft 35 23 mounted in bearings 24, and 25 secured on the outer side of the car body, preferably to the door post 16, by means of screws, bolts, or other suitable devices. Rock shaft 40 23 is capable of slight vertical, as well as oscillatory movements, and it is provided at its upper and lower ends with eccentric lock lugs 26 that are engageable with lock notches, or detents 27 and 28 formed in the 45 door carrying and guiding bars 8 and 9. When lock lugs 26 are engaged with notches 27, the door 8 will be locked in its extreme open position, but when said lugs 26 are engaged with notches 28, the door will be 50 locked in its closed position.

Rock shaft 23 is provided with an arm 29, the hub of which is rigidly secured to said rock shaft and is provided with a beveled undersurface 30 that is engageable with a 55 correspondingly beveled upper surface of the shaft bearing 25. The arrangement of the said beveled surfaces is such, that, under the action of gravity, the rock shaft 23, when free, will swing into a position to engage its eccentric lock lugs 26 with the notches 27 or 28, according to which are aligned therewith. In its free end, arm 29 has a slot 31 that adapts it to be passed over a perforated lug 32 secured on the outer surface of the door 8, when the said door is in

a closed position, and lugs 26 are engaged with notches 28. Either a padlock or a seal passed through the lug 32 when it is projected through the arm 29 will serve to lock the latter and the lugs 26 in position to positively lock or hold the door in its closed position. 70

It will be noted that, in view of the above described tendency of the rock shaft 23 to swing into a door closing position, it will hold the lock lugs 26 against the bars 9 and 10 when the door 8 is in an intermediate position, and will automatically swing its lugs into the aligned notches 27 and 28, so that the door will be automatically latched or locked in either extreme position to which it is moved. 80

What I claim is:

1. The combination with a car body having a door opening, of a door mounted to 85 slide on said car body to open and close said door opening, and a plurality of gate bars slidably mounted in the car body for movements across said door opening and having separate detachable interlocking engagement 90 with said door, and whereby they may be slid with the door or disconnected therefrom.

2. The combination with a car body having a door opening, of a door mounted to 95 slide on said car body to open and close said door opening, a plurality of gate bars slidably mounted in a car body for movements across said door opening and each having a detachable connection with said door and whereby they may be slid with the door or 100 disconnected therefrom, and means positively interlocking said bars to said door when the latter is in an extreme open position.

3. The combination with a car body having a side door opening, of a sliding door movable to open and close said door opening and provided with an inwardly projecting flange at its inner edge, and a plurality of independently movable gate bars slidably 110 mounted in the car body for movements across said door opening, one of the door posts having pockets to receive the extended ends of said gate bars, and a flange carried by the inner edge of said door and provided with slots through which the extended ends of said gate bars are adapted to be projected into the pockets of said door post, said gate bars having interlocking engagement with said flange and when engaged with the 120 pockets of said post when the door is open, being held thereby positively interlocked to said door flange. 115

4. The combination with a car body having a side door opening, of a door slidably 125 mounted on said car body to open and close said door opening, an angle bar secured to one edge of said door with its flange projecting laterally inward to overlap the adjacent door post, said flange having slots 130

and said post having pockets substantially aligned therewith, and a plurality of independently movable gate bars slidably mounted in the car body for movements across the 5 door opening and provided at their free ends with notched latch plates that are freely movable in and out through the slots of said door flange, for interlocking engagement with said flange, when said door is moved 10 to its extreme open position, said pockets operating to hold said gate bars interlocked to said door flange when said gate is in an extreme open position.

5. The combination with a car body having a door opening, of upper and lower bars 15 slidably mounted on the car body, respectively above and below said door opening, a door secured to said upper and lower bars, an upright rock shaft journaled in bearings 20 on said car body adjacent to one side of said door opening, said rock shaft having eccentric lock lugs and said door supporting bars having detents with which said lock lugs are engageable.

25 6. The combination with a car body having a door opening, of upper and lower bars slidably mounted on the car body, respectively above and below said door opening, a door secured to said upper and lower bars, 30 an upright rock shaft journaled in bearings on said car body adjacent to one side of said door opening, said rock shaft having eccentric lock lugs and said door supporting bars having detents with which said lock 35 lugs are engageable, both when said door is in a closed position and when said door is in an open position.

7. The combination with a car body having a door opening, of upper and lower bars 40 slidably mounted on the car body, respectively, above and below said door opening, a door secured to said upper and lower bars, an upright rock shaft on said car body adjacent to one side of said door opening, bearings 45 in which said shaft is journaled, one of which has a beveled upper surface, said rock shaft having eccentric lock lugs and said door supporting bars having detents with which said locklugs are engageable, said 50 rock shaft having a hub with a beveled undersurface with which the beveled surface of said beveled shaft bearing is engaged, the said beveled surfaces acting under the force of gravity to automatically move said lock 55 lugs into interlocking engagement with the detents of said upper and lower bars.

8. The combination with a car body having a door opening, of upper and lower bars slidably mounted on the car body, respectively above and below said door opening, 60 a door secured to said upper and lower bars, an upright rock shaft on said car body adjacent to one side of said door opening, bearings in which said shaft is journaled, one of which has a beveled upper surface, said 65 rock shaft having eccentric lock lugs and said door supporting bars having detents with which said lock lugs are engageable, said rock shaft having a hub with a beveled undersurface with which the beveled surface of said beveled shaft bearing is engaged, the said beveled surfaces acting under the force of gravity to automatically move said lock lugs into interlocking engagement with the detents of said upper and 70 lower bars, both when said door is in a closed and in an open position, said rock shaft further having a radially projecting arm with a slot therein, and said door having a perforated lug with which the slot of 75 said arm is engageable when the door is in a closed position.

9. The combination with a box car having the usual door opening and a sliding door closing the same, a closure structure of 80 spaced members normally attached to the side of the door and slideable across the door opening when said sliding door is open, and means for varying the number of said spaced 85 members used.

10. The combination with a box car having the usual door opening and a sliding door closing the same, of a closure structure of spaced members normally attached to the side of the door and slideable across the door opening but separately detachable from said door when the said sliding door is open, and means for locking said closure in position across the door opening when the door is in fully opened position.

11. In a box car structure having the usual door opening, a sliding door movable to close said opening, a closure of spaced horizontal members each detachably connected at one of its ends to the door on one side 95 thereof adapted to be moved across the door opening as the sliding door is opened, and means for supporting and spacing the other end of said horizontal members.

In testimony whereof I affix my signature. 100

JOHN EDMAN.
